HIGH-FREQUENCY AMPLIFIERS, RADIO
TRANSMITTERS, AND THE LIKE

Ernest Green and Victor Owen Stokes, Chelmsford, England, assignors to Radio Corporation of America, a corporation of Delaware

Application December 12, 1947, Serial No. 791,212
In Great Britain December 6, 1946Section 1, Public Law 690, August 8, 1946
Patent expires December 6, 1966

10 Claims. (CL 178—44)

1

This invention relates to high frequency amplifiers, radio transmitters and other apparatus of the kind in which, in order to obtain a large output power, two output stages driven by a common driving unit and supplying a common load circuit are employed.

Arrangements in which a common driving unit drives two output stages (hereinafter called final stages) which feed into a common load are frequently employed in radio transmitters. However, a difficulty which is often experienced is that if the operating frequency is high and there is a number of intermediate stages—either frequency multiplier or amplifiers or both—between the common driving unit and the final stages feeding the common load, relative phase shift between the outputs from the final stages may occur causing overloading and inefficiency. The main object of the present invention is to avoid this difficulty.

According to this invention a high frequency arrangement of the kind in which a common load is fed from a plurality of final stages driven by a common driving source comprises means, operated in dependence upon the relative phase or phases between the outputs of the final stages, for automatically controlling the tuning of at least one circuit in each of the channels to said final stage output circuits or in all but one of said channels so as to automatically vary said tuning in a direction to correct for any departure of said relative phase or phases from a predetermined value or values. In practice the predetermined relative phase or phases will, in general, be that of the in-phase condition.

The automatic tuning control may be applied in all the channels leading to the final stages or the objects of the invention can be achieved by effecting automatic tuning control in all but one of the channels. In the simplest case where there are only two channels the objects of the invention can be achieved, therefore, by applying automatic tuning control in only one channel but in this case control in both channels is preferred.

Preferably also the automatic tuning control is effected by one or more electron discharge tubes connected and operated to act as variable reactances which are controlled by the output or outputs from a phase discriminator circuit or

2

circuits actuated by energy taken from the final stages.

The invention is illustrated in the accompanying diagrammatic drawings, in which like references are used for like parts.

Figure 1 shows, in block form, the general arrangement of one embodiment of the invention.

Figure 2 shows a preferred and very simple form of phase discriminator circuit in accordance with the present invention.

Figure 3 shows a form of phase discriminator which may be employed as an alternative to that of Fig. 2.

Figure 4 shows single double-controlled variable reactance tube which may be used instead of the two reactance tubes of Fig. 1.

Referring first to Fig. 1 which shows, in block diagram form, the general arrangement of one embodiment of the invention, the radio transmitter installation therein represented comprises a common drive unit 1 driving through two separate channels generally designated 2, 3 two final output stages 4, 5 which supply energy to a common load 6. Each channel includes a desired number of frequency multipliers and/or amplifiers 7, 8 in cascade. Automatic tuning control is effected preferably at an early stage in each channel by means of tubes operated as variable reactance tubes, there being one such variable reactance tube appropriate to each channel. These tubes are included, in Fig. 1, in the blocks 9, 10. Outputs from the two stages 4, 5, are fed as usual to the common load 6 and also to a phase discriminator network 11 which provides control potentials in dependence upon the relative phase between the final stage outputs, said control potentials being fed back to the reactance tubes at 9, 10 to control the effective reactances presented thereby.

The reactance tubes are, of course, included in the frequency determining circuit whose tuning is to be controlled and the automatic control is such that if the final stages depart from the desired in-phase relation the tuning of the circuits with which the reactance tubes are associated are oppositely varied to correct for such departure.

The actual discriminator circuits and reactive tube circuits may take any of a variety of forms. A preferred and very simple form of phase discriminator circuit in accordance with the pres-

ent invention is shown in Fig. 2 which is a representation of the transmitter installation of Fig. 1 in more detail. In Fig. 2 the phase discriminator circuit, generally designated 11, comprises a pair of diodes V_2V_2' (or other rectifiers) whose anodes are connected together through a resistance R_1 shunted by a first parallel tuned circuit C_1L_1 . The cathodes of the diodes are connected to earth through separate load resistances R_2R_2' each shunted by a suitable bypass condenser as shown. If desired, meters M, M' may be included in series with the load resistances. A second parallel tuned circuit C_2L_2 is connected between the mid-point of the coil or condenser of the tuned circuit L_1C_1 and earth. As shown the coil L_1 is centre tapped for this purpose. These two tuned circuits are coupled as indicated by the arrows one to each of the output circuits of the final stages 4, 5 said coupling being preferably effected as near to the common load circuit 6 as possible. The coupling may conveniently be effected inductively between the coils L_1L_2 of the tuned circuits and the feeders from the stages 4, 5 to the common load circuit 6 and if desired, the said coupling may be adjustable. An adjustable tap on each diode load resistance R_2R_2' is connected through a suitable further resistance R_3R_3' and/or bias supply (not shown) to the control electrode of one or other of two variable reactance tubes V_1V_1' , associated with tuned circuits $L_3C_3, L_3'C_3'$ in the early stages 9, 10 in the channels 2, 3 from the common drive unit 1. If the phase discriminator is arranged to give an output of negative polarity no bias supply sources in the leads to the grids of V_1V_1' will be required. The variable reactance tube circuits may be of any kind known per se, for example, they may include pentodes and provision may be made for manual adjustment, e. g. by providing them with variable cathode leg resistances R_4R_4' as indicated.

The first tuned circuit L_1C_1 connected between the anodes of the diodes is tuned substantially to resonance at the working frequency while the second tuned circuit L_2C_2 is resonant at a frequency well away from this frequency. Thus the voltage across these two circuits when the two final stage output currents are in phase will be nearly in quadrature and can be adjusted accurately in quadrature by slightly mistuning the first tuned circuit L_1C_1 . Assuming symmetry in the diode circuits the rectified currents in the load resistances R_2R_2' will be equal so long as the quadrature relation is maintained but if the currents from the final stages 4, 5 depart from the in-phase relation the currents in the said load resistances R_2R_2' will become unequal and the consequent control voltages fed back to the reactance tubes V_1V_1' will produce tuning changes in the two channels to correct for the inequality, e. g. to correct for departures from the desired in-phase relation.

An auxiliary monitor circuit (not shown) comprising an additional tuned circuit and a rectifier and meter equally but oppositely coupled to both feeders should be provided in order to insure that the final stage outputs are in correct phase and not 180° apart. The meter will give a minimum reading when the phasing is correct. Such a monitor circuit may be arranged to operate visual and/or aural indicating means when a predetermined level is exceeded and automatically to open the main H. T. supplies when a still higher predetermined level is passed so as to provide automatic protection against damage.

in the event of a failure of the automatic phase sensitive control means.

Obviously only one diode or other rectifier may be employed and phase control applied to one channel only, the other being set to a mean phase. The symmetrical arrangement of Figs. 1 and 2 is, however, preferred.

In a modified form of phase discriminator shown in Fig. 3 and which may be employed as an alternative to that of Fig. 2 the diodes V_2, V_2' are replaced by grid controlled tubes GV_2GV_2' for example triodes as shown, having their control grids connected together and earthed through a suitable resistance R_5 . The first or "in-tune" parallel tuned circuit L_1C_1 shunted by resistance R_1 is connected between the anodes of the triodes and the mid-point of the coil of this circuit is earthed. The second or "off-tune" parallel tuned circuit L_2C_2 is connected between the common grid point of the triodes and earth. In other respects the phase discriminator is as in Fig. 2 and control voltages for the reactance tubes V_1V_1' (not shown in Fig. 3) are taken off from taps on resistances R_2R_2' in the cathode legs of the triodes GV_2GV_2' . Again as before, the circuit settings are such as to obtain a quadrature relation between the voltages across the two parallel tuned circuits L_1C_1, L_2C_2 when the outputs from the final stages are in phase.

It is not necessary to provide two separate variable reactance tubes such as V_1V_1' , one in association with each channel 2, 3 for as shown in Fig. 4 a single double-controlled variable reactance tube V_{11} may be employed in conjunction with a symmetrical phase discriminator network such as that shown in Fig. 2 or in Fig. 3 by applying one controlling output from R_2 of the discriminator network (not shown in Fig. 4) to a grid of the reactance tube V_{11} and the other controlling output from R_2' to another electrode, for example, the cathode of the said tube V_{11} .

In some cases the output stages 4, 5 may be used as a phase discriminator, because when the relative phase of the outputs from two channels changes in one sense the anode feed of one output stage will rise, whilst that of the other will fall. When the relative phase changes in the opposite sense these conditions are reversed. Resistances connected between the cathodes and earth in the output stages 4, 5 can be used to provide two voltages to control the reactance valve or valves in the same way as before.

Where the outputs of several final stages are to be supplied to a common load, it is preferred to use one output stage as a reference, providing phase discriminators and monitors to compare the phase of all other outputs with this. Each phase discriminator would then control a reactance valve in its own transmitter.

Where a common modulation is applied to the final stage outputs means should be provided for preventing such modulation from affecting the operation of the reactance tube or tubes. Such means may take any convenient form known per se, for example, smoothing and limiting circuits.

What is claimed is:

1. In a circuit arrangement for maintaining an in-phase relation between alternating voltages fed by a plurality of signal channels to a common load, means responsive to the relative phase between the outputs of said channels for developing a control voltage of a magnitude dependent upon such relative phase, voltage responsive means in at least one of said channels for controlling the tuning of such channel, and

means for applying said control voltage to said last-named means to vary the tuning of the controlled channel in a direction to correct for any departure of said relative phase from a predetermined value.

2. In a circuit arrangement for maintaining an in-phase relation between alternating voltages fed by a pair of signal channels from a common driving source to a common load, means responsive to the relative phase between the outputs of said channels for developing a pair of control voltages of magnitudes dependent upon such relative phase, separate voltage responsive means in each of said channels for controlling the tuning of such channels, and means for applying said control voltages separately to each of said last-named means to vary the tuning of each corresponding channel in a direction to correct for any departure of said relative phase from a predetermined value.

3. In a circuit arrangement for maintaining an in-phase relation between alternating voltages fed by a plurality of signal channels to a common load, means responsive to the relative phase between the outputs of said channels for developing a control voltage of a magnitude dependent upon such relative phase, variable reactance tube means in at least one of said channels for controlling the tuning of such channel in response to a voltage applied to such means, and means for applying said control voltage to said reactance tube means to vary the tuning of the controlled channel in a direction to correct for any departure of said relative phase from a predetermined value.

4. A circuit arrangement as defined in claim 3, wherein a separate variable reactance tube is provided for controlling tuning of each channel which is subjected to such control, wherein the control voltage developing means produces a plurality of control voltages, and wherein each such tube has applied thereto a separate single control voltage from the control voltage developing means.

5. A circuit arrangement as defined in claim 3, wherein a single grid-controlled variable reactance tube is provided for controlling tuning of one channel which is subjected to such control, wherein the control voltage developing means produces two control voltages, and wherein said single tube has applied thereto said two voltages from the control voltage developing means, one voltage being applied to the cathode of said tube and the other to the grid of said tube.

6. In a circuit arrangement for maintaining an in-phase relation between alternating voltages fed by a plurality of signal channels to a common load, at least one discriminator circuit having a pair of input resonant circuits, one of which is resonant at substantially the predetermined output frequency of the channels and the other of which is resonant at a frequency displaced therefrom, said resonant circuits being coupled each to a separate one of the channel outputs adjacent the common load, means connecting said resonant circuits in a rectifier circuit providing two equal control output potentials so long and only so long as the voltages across the two resonant circuits are substantially in phase quadrature, separate voltage responsive means in two of said channels for controlling the tuning of such channels, and means for applying said two control output potentials separately to each of said last-named means to vary the tuning of each corresponding channel

in a direction to correct for any departure of the voltages across the two resonant circuits from a phase quadrature relationship.

7. A circuit arrangement as defined in claim 5, wherein the rectifier circuit includes two rectifiers, wherein said one resonant circuit is center-tapped and connected between corresponding terminals of said rectifiers, and wherein said other resonant circuit is connected between said center tap and a point of fixed potential, said rectifiers having impedances, connected respectively between the remaining terminals thereof and a point of fixed potential, in which said two control output potentials respectively appear.

15 8. A circuit arrangement as defined in claim 6, wherein the rectifier circuit includes two grid-controlled tubes having a common grid terminal connected to a point of fixed potential through an impedance, wherein said one resonant circuit 20 is connected between the anodes of said tubes and has its center point connected to a point of fixed potential, and wherein said other resonant circuit is connected between said common grid terminal and a point of fixed potential, said 25 tubes having impedances, connected respectively between the cathodes thereof and a point of fixed potential, in which said two control output potentials respectively appear.

9. In a circuit arrangement for maintaining an in-phase relation between alternating voltages fed by a pair of signal channels to a common load, said channels each including an input stage having therein a circuit the tuning of which determines, at least in part, the relative phases of 30 the alternating voltages fed to said load: a reactance tube in each of said channels connected in shunt to the said circuit therein for tuning the same; a discriminating and detecting network coupled to the outputs of both of said channels 35 for comparing the phases of the voltages fed by the channels to the said common load, said network including a plurality of electron discharge devices connected in rectifier circuits having impedances wherein potentials are developed of a magnitude dependent on the relative phase of 40 the alternating voltages in the outputs of the channels; and means for applying said developed potentials separately to the control electrodes of corresponding reactance tubes.

10. In a circuit arrangement for maintaining an in-phase relation between alternating voltages fed by two signal channels to a common load, said channels each including an input stage having therein a circuit the tuning of which determines at least in part the relative phases of 50 the alternating voltages fed to said load: a reactance tube in each of said channels connected in shunt to the said circuit therein for tuning the same; a discriminating and detecting network coupled to the outputs of both of said channels 55 for comparing the phases of the voltages fed by the channels to the said common load, said network including a pair of electron discharge devices each having a cathode connected to ground 60 by an impedance, a resonant circuit coupled to the output of one channel and connected between like electrodes of said tubes, and a circuit detuned with respect to said last-named circuit coupled to the output of the other channel and connected 65 cophasally to like electrodes of said tubes, whereby potentials of a magnitude dependent on the relative phase of the alternating voltages in the outputs of the channels are developed in said impedances; means for applying one of the 70 developed potentials to the control electrode of

one of the reactance tubes; and means for applying the other developed potential to the control electrode of the other reactance tube.
